Primary Examiner — Cynthia M. Chin

(57) **CLAIM**

The ornamental design for a tent, substantially as shown and described.

DESCRIPTION

FIG. 1 is a front and right side perspective view of tent, showing my new design;

FIG. 2 is a rear and right side perspective view thereof;

FIG. 3 is a top view thereof;

FIG. 4 is a bottom view thereof;

FIG. 5 is a front view thereof;

FIG. 6 is a rear view thereof;

FIG. 7 is a right-side view thereof; and,

FIG. 8 is a left-side view thereof.

The broken lines in the drawings illustrate the portions of the tent, which form no part of the claimed design.

1 Claim, 8 Drawing Sheets(56)
